UNITED STATES PATENT OFFICE.

MARION J. HARDEN, OF AKRON, OHIO.

IRONING-BOARD CABINET.

1,193,847.

Specification of Letters Patent. Patented Sept. 12, 1916.

Application filed July 19, 1916. Serial No. 110,139.

To all whom it may concern:

Be it known that I, MARION J. HARDEN, a citizen of the United States, residing at Akron, in the county of Summit and State 5 of Ohio, have invented a new and useful Ironing-Board Cabinet, of which the following is a specification:

The object of the invention is to provide a simple and convenient cabinet for holding 10 ironing boards and related paraphernalia and for supporting said boards in operative position for use.

Further objects of the invention will appear as the description proceeds, it being understood that changes in the precise embodiment of the invention herein disclosed, 15 can be made within the scope of what is claimed, without departing from the spirit of the invention.

20 In the accompanying drawings:—Figure 1 is a front view of a cabinet constructed in accordance with the invention. Fig. 2 is a vertical sectional view showing an ironing board in operative relation thereto. Figs. 25 3, 4 and 5 are detail views of modified constructions of boards.

The cabinet 10, which may be secured to a wall or other vertical support in any convenient manner, is provided with a door 11 and preferably a lower compartment or drawer 12, a rest or platform 13 being interposed between said drawer space and the body portion of the interior of the cabinet. Secured transversely to this rest or platform 35 is a detent bar or cleat 14, and projecting forwardly from the rear wall of the cabinet is a ledge 15 beneath which the rear end edge of the board 16 may be engaged, said board being provided with a cleat 17 to 40 be engaged with the detent or cleat 14 to provide for holding the board against longitudinal displacement while in use. Obviously to arrange the board for use it is only necessary to incline it downwardly, 45 toward its rear or inner end and after en-

gagement with the ledge 15 it may be depressed at its outer end to cause engagement of the cleats.

Obviously a plurality of different shapes of boards may be used in connection with 50 the holding means, and when not in use these boards may be stored in the cabinet, the detent or cleat 14 serving when the boards are thus stored, as a means of preventing accidental displacement of the lower ends thereof, while a downwardly extending spacing strip 18 constituting a portion of the front wall of the cabinet may serve a similar function for the upper end of the board when arranged in the cabinet, as indicated by 55 dotted lines in Fig. 2.

The drawer 12 may be utilized as a receptacle for the storage of various articles including the iron, etc., and a socket 19 may be conveniently arranged on the cabinet for 60 the attachment of an electric iron.

Obviously the rest or platform 13 can be arranged at a convenient height so as to properly support the board when in operative position thereon.

What is claimed is:

An ironing board cabinet having a board receiving compartment and a horizontal platform or rest, a transverse ledge arranged adjacent to and above the plane of 75 said platform or rest, a board adapted for terminal engagement with said ledge, said board and platform or rest having engaging transverse cleats, and the cabinet at its top having a depending spacing strip terminating at less than a board's length distance 80 from the plane of the platform or rest.

In testimony that I claim the foregoing as my own, I have hereto affixed my signature in the presence of two witnesses.

MARION J. HARDEN.
